UNITED STATES PATENT OFFICE.

AXEL C. V. MALM, OF DAYTON, OHIO, ASSIGNOR TO THE EGRY REGISTER COMPANY, OF DAYTON, OHIO, A CORPORATION OF OHIO.

MOTOR AND STOP MECHANISM FOR AUTOGRAPHIC REGISTERS.

1,203,028.

Specification of Letters Patent.

Patented Oct. 31, 1916.

Application filed February 7, 1916. Serial No. 76,505.

To all whom it may concern:

Be it known that I, AXEL C. V. MALM, a citizen of the United States, residing at Dayton, in the county of Montgomery and State of Ohio, have invented certain new and useful Improvements in Motor and Stop Mechanism for Autographic Registers, of which the following is a specification, reference being had therein to the accompanying drawing.

This invention relates to autographic registers.

The object of the invention, broadly stated, is to provide an organization of mechanism by which this class of registers can be motor-operated, the medium for driving the motor being preferably electricity.

The preferred construction and organization of mechanism are disclosed in the accompanying drawings and described in this specification, as one embodiment of the invention.

Among the special features are devices which, when the motor is cut off from the register, will automatically retard the momentum of the moving parts of the register, to prevent shock, and to enable the definite stopping of the mechanism at a given point coinciding with the limit of the paper-feeding movement of the register.

In the accompanying drawings, Figure 1 is an elevation of the mechanism, partly in section; Fig. 2 is a sectional side elevation on the line 2—2 of Fig. 1, looking in the direction of the arrows; and Fig. 3 is a plan view of the mechanism with parts in section on the line 3—3 of Fig. 1.

In the embodiment of the invention here shown the register casing is indicated by the numeral 1. Within this casing is mounted a shaft 2 having thereon spaced pin wheels 3 and 4 which project above the support 5 on which the webs of paper to be fed lie. Above the support 5 is the register lid 6 having means 7 thereon to hold the webs of paper in engagement with the teeth and against the support. Secured to the shaft 2 is a gear 8 which meshes with a gear 9 suitably journaled within the casing, the gear 9 meshing with a gear 10 fixed to a shaft 11 suitably journaled within the casing 1. The mechanism above described is the usual mechanism found in registers of this nature and upon the outer end of the shaft 11 is

usually located the crank handle for operating the same. The invention herein described is adapted to be attached to the above described mechanism.

A suitable source of power 12 which, in the present instance, is an electric motor, is mounted within a frame 13 adjacent the casing 1 of the register. A driving shaft 14 having a pinion 15 thereon is arranged to be rotated by the motor. A system of double compound gearing to reduce the speed of the motor when applied to the feeding mechanism is interposed between the pinion 15 and the feeding mechanism. This system of gearing, as here shown, although any other type of transmission may be used, comprises a gear 16 meshing with the pinion 15 and fixed to a suitably journaled shaft 17. Motion is transmitted from the shaft 17 through a gear 18 fixed thereto to a gear 19 fixed to the shaft 20. The shaft 20 has fixed thereto a gear 21 which meshes with a gear 22 located at the end of the shaft 11. This gear 22 takes the place of the ordinary handle on registers of this nature. Mounted adjacent the register upon the upper portion of the frame 13 is a pair of spaced blocks of insulating material 23. Metallic contacts 24 are suitably fixed to the bottoms of these blocks of insulating material and project inwardly toward each other. Conducting wires 25 lead from these contacts and are suitably connected to the motor 12. Mounted above the casing on the outside thereof is the usual button switch casing, indicated at 26. Slidably mounted within said casing 26 is an insulated button 27 having at its lowered end an insulated member 28 carrying contact members to which are connected in any suitable manner the conducting wires 29. These wires can be connected to any source of electrical energy, such as the socket of a lighting system. The button 27 is extended below the member 28, as shown at 30, and comprises an abutment thereon, as shown at 31, a notched portion, as shown at 32, and a wedge, as shown at 33, the purposes of which will be described hereinafter. A bracket 34 projects downward from the upper portion of the frame 13, this bracket comprising a pair of spaced arms, 35 and 36, through which the extending portion 30 projects. The upper portion of the bracket forms a shoulder 37

and this shoulder with the collar 31 constitutes a pair of abutments between which a spring 38 is located to keep the circuit normally open. A lever 39 is pivoted between its ends to the end of the arm 36, as indicated at 40. The lower end of this lever is located within the space between the arms 35 and 36 and a spring 41 connects the same to the bracket, the spring exerting a tension upon the lower end of the lever to move the same rearwardly against the extending portion 30, as shown in Fig. 1. The upper end of the lever 39 lies closely adjacent to the outer face of the gear 22. This gear has mounted thereon a cam lug, as indicated at 42. A pin 43 is slidably mounted within the lower arm 35 of the bracket 34. This pin has an inclined surface 44 coöperating with the wedge-shaped end 33. The pin is normally held in projected position by a spring 45, the projecting end of the pin abutting against the surface of the gear 22. In the position shown in the drawings this pin is projecting into a hole 46 in said gear to lock the entire mechanism against movement. Fixed to the shaft 2 intermediate the pin wheels 3 and 4 is a friction pulley 47. A pair of friction bands 48 extend both above and below the friction pulley 47. These bands are held in a clamping device 49 attached to a fixed shaft 50 mounted on the casing of the register. The tension of the straps can be adjusted by means of a screw 51 which connects the ends of the straps opposite to the clamping device.

The operation of the mechanism is substantially as follows: It is generally customary to feed a definite amount of paper at each operation. In the present case a complete revolution of the gear 22 feeds the required amount of paper and it is essential that the operation of the device ceases at the instant that a complete revolution is made. When it is desired to operate the machine the button 27 is depressed and this will cause the inclined surface 33 to engage the inclined surface 44 and retract the pin 43 from the hole 46. The mechanism is thereby unlocked. Further movement of the button 27 closes the circuit and the motor begins to rotate. The rate of rotation of the motor, of course, is relatively very great and a reducing mechanism is interposed between the same and the feeding device. This mechanism will cause the rotation of the pin wheels at the proper rate. The retarding device does not unduly retard this rotation. After the circuit has closed the spring 41 will cause the lower end of the lever 39 to project into the notch 32 of the extending portion 30, thereby securely locking the same in its lowered position. At the same time the upper end of the lever will be projected closely adjacent to the surface of the gear 22. As the mechanism ro-

tates the cam lug will engage the upper end of the lever, causing the same to move back, the lower end of the lever moving forward and disengaging from the notch 32. The disengagement of the lever 39 from the notch 32 allows the button 27 to rise and open the circuit. At the same time the pin 43 engages the side of the gear 22. As the power is shut off from the motor the inertia would continue the rotation of the mechanism if it were not for the retarding device above described. This retarding device, it will be noticed, is located upon the shaft 2 at a point remote from the source of power. It will be seen that a very small retarding force at this point on account of the leverage through the reducing gear will rapidly retard the motor and the adjacent mechanism. Immediately after this retarding force has become effective the hole 46 comes in alignment with the pin 43, the pin thereby entering the hole and locking the mechanism against further movement. It should be noticed that the cam lug 42 and the hole 46 are so located that the pin will not enter said hole after the current has been shut off by the engagement of the cam with the lever until the retarding device has sufficiently retarded the mechanism so that there will be no danger of shearing or breaking the pin or any of the other parts. The retarding device including the friction pulley and the band can be so regulated as to properly time the retarding effect so that the hole will come into alignment with the pin at the proper moment. Attention is called to the ease with which this mechanism can be operated. A single pressure upon the button 27 is all that is necessary. The motor will then rotate the feeding mechanism steadily and quickly, the button 27 remaining locked in position until nearly a complete revolution is made. The current is then shut off automatically and the retarding device comes into operation to retard the mechanism. After the mechanism has been sufficiently retarded and at the instant the necessary amount of paper has been fed the mechanism locks automatically with a minimum stress being exerted thereon.

In the embodiment of the invention here shown the cam lug and hole to receive the locking device are situated upon the gear 22 which takes the place of the handle, as mentioned above. By this arrangement the present improvement can be applied very easily to the types of registers now in use, but it is to be understood, however, that the invention is not limited to this location of the cam lug and hole. The locking device and the automatic feature for opening the circuit can be applied to any part of the mechanism.

While I have shown and described one

embodiment of the invention it will be understood that this has been chosen for the purposes of illustration only, and that I do not desire to be limited to the details of 5 construction shown and described, for obvious modifications will occur to a person skilled in the art.

Having thus fully described my invention, what I claim as new and desire to secure by 10 Letters Patent, is:—

1. In a mechanism of the character described, a feeding device, an electric motor operatively connected to the same, a switch for controlling the circuit through said motor, a lock for the feeding device operatively connected to said switch, whereby a movement of one actuates the other and automatic means for controlling said switch and lock to open the circuit and lock the feeding device against movement. 20

2. In a mechanism of the character described, driven mechanism, an electric motor therefor, a retarder associated with said driven mechanism, a circuit closer controlling the circuit through said motor, a locking device for said driven mechanism operatively connected to said circuit closer, whereby the movement of one moves the other, and automatic devices controlling the circuit to break the same and the locking device to positively lock the driven mechanism. 30

3. In a mechanism of the character described, a driven mechanism, an electric motor for the same, means for locking said driven mechanism, a switch for successively releasing said locking means and closing the circuit through said motor, a device for retaining said switch in closed circuit position, and automatic means for controlling said device. 40

4. In a mechanism of the character described, a feeding device, a retarder associated with said feeding device, an electric motor, speed reducing transmission gears interposed between said motor and feeding device, a switch, means for positively locking said feeding device when the circuit through said motor is broken, and means controlled by certain of the moving parts for controlling the switch and locking means to open the circuit and lock the feeding device against movement. 50

5. In a mechanism of the character described, a feeding device, a motor, a slidable pin adapted to engage and disengage the feeding device to lock the same, a circuit closer provided with a portion to disengage the pin and movable to close the circuit, and automatic means controlling said circuit closer and pin to open the circuit and lock the feeding device against movement either forwardly or rearwardly. 60

6. In a mechanism of the character described, a feeding device, means for actuating said feeding device, a locking pin slid-

ably mounted upon a fixed part of the frame, means for retracting said pin, means for holding said pin in retracted position, means controlled by the moving part for actuating said last-mentioned means to release the pin, 70 and a hole in one of the moving parts with which the pin engages to prevent the forward movement and recoil of the feeding device.

7. In a mechanism of the character described, a feeding device, a motor for actuating said feeding device, a switch controlling the circuit through said motor, a locking device to lock said feeding device against movement, a pivoted lever for retaining said switch in closed circuit position and said locking device in disengagement with the feeding device, and a cam on one of the moving parts to engage the lever, whereby the circuit is open and the locking device engages 85 the feeding device. 75

8. In a mechanism of the character described, a feeding device, a motor for actuating said feeding device, a locking pin movable at right angles to the path of rotation of certain of the moving parts, means for withdrawing said pin from locking position and closing the circuit, a device for retaining said means in such position, a retarder associated with said feeding device, and means 90 for automatically controlling said circuit closer and locking pin. 95

9. In a mechanism of the character described, a feeding device, a motor, transmission devices interposed between said motor and said feeding device, a fixed frame, a locking device mounted on said frame, a switch controlling the circuit through said motor, said switch being operatively connected to said locking device, whereby when one 100 is operated the other also will be operated to close the circuit and disengage the locking device, a retarder associated with said feeding device, and automatic means for controlling the switch and locking device to open 110 the circuit and lock the feeding device against movement. 105

10. In a mechanism of the character described, a feeding device, a retarder associated with said feeding device, a motor, transmission gearing interposed between said motor and said feeding device, a slidable pin mounted on the frame work and normally held projected by means of a spring into the path of the transmission gearing, a push button for controlling the circuit through said motor and provided with an extension in engagement with said pin, whereby the pin will be retracted against the pressure of its spring and the circuit will be closed, a centrally pivoted lever provided with a spring which holds one end thereof normally in engagement with said projecting portion of said push button, whereby the locking pin is held retracted and the circuit closed, and a 130 115 120 125

cam mounted upon the transmission gearing and arranged in the path of the opposite end of said lever.

11. In a mechanism of the character described, a feeding device, a retarder associated with said feeding device, a motor, speed reducing transmission devices interposed between said motor and feeding devices, a switch for controlling the circuit through said motor, a locking device for positively locking said feeding device against forward movement and recoil, and means controlled by the transmission devices for controlling said switch and locking device.

15 12. In a mechanism of the character described, a driven mechanism, a source of power for actuating said driven mechanism, a locking device to lock said driven mechanism against movement, common means for 20 rendering said locking device inoperative and causing said source of power to actuate said driven mechanism, a device to lock said common means to hold said locking device in its inoperative position and to continue the actuation of said driven mechanism, and means on said driven mechanism to engage said last-mentioned locking device to unlock the said common means to allow the same to render the source of power inoperative and to allow the locking device to assume an operative position.

13. In a mechanism of the character described, a driven mechanism, a motor operatively connected to said driven mechanism, 25 a locking device to lock said driven mechanism against movement, a circuit closer, means on said circuit closer to render said locking device inoperative, a device for locking said circuit closer in its 40 closed position, means on said driven mechanism arranged to engage the last-mentioned locking device to unlock said circuit closer to allow the same to break the circuit and permit the first-mentioned locking device to engage said driven mechanism.

45 14. In a mechanism of the character described, a driven mechanism, a source of power, a device for locking said driven mechanism against movement, means movable to make said locking device inoperative and to make said source of power operative, a device to lock said means in adjusted position, means on said driven mechanism arranged to engage said last-mentioned locking device to release said movable means to render the first-mentioned locking device operative and the source of power inoperative, means to retard said driven mechanism after the source of power has become 55 60 inoperative, and means associated with said driven mechanism and arranged so as to engage said first-mentioned locking device after the retardation of said driven mechanism.

15. In a mechanism of the character de-

scribed, a driven mechanism, a source of power, means for controlling said source of power, a retarder associated with said driven mechanism, a locking device comprising a slideable pin and a hole in one of the moving parts of the driven mechanism, and automatic devices controlling the means for controlling the power to render the same inactive and for controlling the locking device to allow the pin to engage the hole to lock the driven mechanism against forward movement and recoil.

16. In a mechanism of the character described, feeding devices, an electric motor operatively connected to said feeding devices and provided with a speed reducing device and a retarding device, a switch controlling the circuit through said motor, and a lock automatically controlled after a definite feeding movement of the feeding devices for positively locking the feeding devices against movement after the power has been cut off and the mechanism retarded, whereby the amount of movement of the feeding devices at each operation of the mechanism is definite and limited.

17. In a mechanism of the character described, feeding devices, a retarder associated therewith, an electric motor, speed reducing transmission devices interposed between said motor and feeding devices, a switch controlling the circuit through said motor, and a lock automatically controlled for locking the feeding device after the power has been cut off to definitely limit the amount of feed thereof.

18. In a mechanism of the character described, driven devices, a retarder associated therewith, an electric motor, speed reducing transmission devices interposed between said driven devices and motor, a switch controlling the circuit through said motor, a lock, and means to definitely limit the amount of feed thereof controlling said switch and lock.

19. In a mechanism of the character described, a feeding device, a source of power operatively connected to said feeding device by moving parts, a retarder associated with the feeding device, a slideable pin mounted in a fixed frame, arranged at right angles to the path of rotation of certain of the moving parts and adapted to engage the same to positively lock the feeding device against forward movement and recoil, means for retaining said pin retracted, and means controlled by certain of the moving parts for controlling said pin and cutting off the power to definitely limit the feed.

20. In a mechanism of the character described, a feeding device, a source of power operatively connected with said feeding device, a locking pin slidably mounted in a fixed part of the frame, transmission devices interposed between said source of

130

power and said feeding device with which said pin engages, common means for successively withdrawing said pin and causing the source of power to become active, a ⁵ detent retaining said means in operative position, and a cam upon the transmission devices adapted to engage said detent, whereby the source of power is cut off and the pin is projected into the path of the moving ¹⁰ parts to lock the feeding device against forward movement and recoil.

21. In a mechanism of the character described, a feeding device, a motor operatively connected to the same, retarding and ¹⁵ speed reducing devices associated therewith, a switch controlling the circuit through said motor, a lock to definitely lock the feeding device after a definite limited movement thereof, and automatic devices for controlling the switch and lock, whereby the feed is uniform and limited at each operation of ²⁰ the mechanism.

22. In a mechanism of the character described, a feeding device, a motor for operating said feeding device, retarding and speed reducing devices associated therewith, a switch controlling the circuit through said motor, a lock for definitely locking said ²⁵

feeding device against movement, and means controlled by moving parts for controlling the switch to open the circuit and the lock to lock the feeding device against movement. ³⁰

23. In a mechanism of the character described, a driven mechanism, a source of power, speed-reducing transmission devices interposed between said source of power and said driven mechanism, a retarder on said driven mechanism, a lock for definitely locking said mechanism after a definite ³⁵ movement thereof, and automatic means for discontinuing the application of power to said transmission devices at the end remote from said retarder and to actuate the lock after said definite movement. ⁴⁰

24. In a mechanism of the character described, a shaft provided with feeding devices, a retarder on said shaft, an electric motor, transmission devices interposed between said motor and shaft, and a switch ⁴⁵ in the motor circuit and lock controlled by said transmission devices for definitely limiting the operation of the feeding devices. ⁵⁰

In testimony whereof, I affix my signature.

AXEL C. V. MALM.
